[57] CLAIM

The ornamental design for a lotto number selector, as shown and described.

DESCRIPTION

FIG. 1 is a top, front and side perspective view of the lotto number selector showing my new design;

FIG. 2 is a top plan view thereof;

FIG. 3 is an end elevational view thereof, all elevational views being similar to FIG. 3 except for length, with side elevational views being longer than end elevational views; and,

FIG. 4 is a bottom plan view thereof.

FIG. 4.
